UNITED STATES PATENT OFFICE

JOSEPH R. RAWLEY, OF NEW YORK, N. Y.

IDENTIFICATION RECEPTACLE FOR UMBRELLAS AND THE LIKE

Application filed May 25, 1928. Serial No. 280,456.

This invention relates to a device which may readily be attached to and removed from the rib of an umbrella frame or other similar member and serve as a receptacle or a container for an identification slip bearing the name and address of the owner or such other information as it may be desired to present. I am quite aware that devices of this general character have heretofore been proposed. The improvements which the present invention contemplates are more particularly in the construction of such an attachment which will facilitate its use and increase its effectiveness while at the same time presenting a more attractive appearance. With these and other objects in view, I employ a pair of longitudinally split tubular or elongated cup-like members, capable of being slipped over the rib of an umbrella and frictionally slidable both longitudinally and rotatively one within the other with the identification slip inserted therein, each tube having its outer end rounded off to a reduced diameter approximating that of the umbrella rib so as to center the assembled container on the rib and at the same time to effectively close the ends of the container against the escape of the identification slip. The turning of one of the tubes with respect to the other enables the unslotted wall of one to close the slot of the other so that the receptacle is prevented from becoming accidentally detached from the umbrella rib. Other improved features of construction will be clearly apparent from a more detailed description of a preferred form of the invention which is illustrated by way of example in the accompanying drawing, in which

Figure 1 is a side elevation of an umbrella with a part of the cover broken away to expose the container mounted on one of the ribs thereof.

Figures 2 and 3 are isometric views of the inner and outer tubular members, respectively.

Figure 4 is a similar view on an enlarged scale illustrating the assembled parts mounted in position on the rib of an umbrella.

Figure 5 is a transverse section thereof on the line 5—5 of Figure 4.

Figure 6 is a detail view of an identification slip to be enclosed in the receptacle or container.

Figure 7 is a perspective view of the parts of the device illustrating the use of the outer member for removing the identification slip from the inner member of the container.

Referring more in detail to said drawing, the inner and outer tubular members 10 and 11 are provided with longitudinal slots 12, 13 extending throughout their length and each having a rounded outer end 14 or 15 terminating in a perforation approximating the diameter of the umbrella rib. The inner end of the inner member preferably terminates in a curved tongue-like portion projecting beyond the slotted portion, as indicated at 16, whereas the inner end of the outer member preferably terminates in a transverse plane at right angles to the axis, as indicated at 17. The curved tongue 16 of the inner member, upon being applied to the end 17 of the form described, readily directs the inner member into the outer member, slightly spreading the latter to develop friction, in assembling the parts, and thus facilitates the application and securing of the attachment to the umbrella rib, as will be apparent. The inner member 10 is in its preferred form provided with a bead 18 near its outer end, this bead serving as a stop against which the end 17 of the outer member 11 engages when the one member is slid into the other. The projection of this bead 18 serves further to prevent the cover of the umbrella from catching on the end 17 of the outer member. A similar bead 19 is preferably formed near the outer end of the outer member 11. In each case the bead 18 or 19 adds to the stiffness or the resilience of the tubular member. Preferably the parts described are made of sheet metal which offers a good springy quality, but obviously the invention may be embodied in constructions of any desired material.

In Figure 6 I have indicated by way of example a slip of paper 20 having space thereon for name, address and remarks. Ob-

viously any suitable material other than paper may be employed for this purpose and any desired information spaces may be provided.

5 One of the tubes, for example the inner tube 10, may be provided with one or more detent lugs 21 in position to enter a recess in the form of a hollow or perforation 22 in the other when the parts are in proper 10 position, to yieldingly lock the tubes against accidental relative movement longitudinally or circumferentially.

In the use of the device, the information slip 20 may, for example, be rolled and 15 slipped into the inner member 16 with the slot 12 thereof left clear to permit the application of tube 10 to the rib of the umbrella. Tube 11 is at the same time passed over the umbrella rib whereupon the inner 20 and outer tubular members may be telescoped one upon the other with their slots 12 and 13 on opposite sides from each other, until the inner end 17 of the member 11 abuts against the bead 18 of the member 10, 25 as clearly illustrated in Figure 4. To remove the attachment from the umbrella, the tubes are slid apart and removed from the umbrella rib whereupon the inner end 17 of the outer member 11 may be inserted into 30 the slot of the inner member where its straight end wall engages the end of the rolled slip of paper 20, as clearly shown in Figure 7, and may be used to push the slip endwise out of the inner tube.

35 The above description will serve to clearly indicate to those skilled in this art the principles of construction and use contemplated by the invention and it will, of course, be apparent that the particular size or precise shape of the parts may be modified from those shown in the drawing, without departing from the scope of the invention. Also it should be noted that the use of the device in connection with the identification of an 40 umbrella is merely illustrative and the invention is not confined to any specific use of the construction shown and described.

I claim:—

1. An article of the character described 50 comprising in combination a pair of telescoping, elongated tubular members each with a longitudinal slot extending throughout its length and each having a reduced outer end constituting a wall provided with 55 a perforation in communication with the longitudinal slot.

2. An article of the character described comprising in combination a pair of telescoping, tubular members each having its 60 outer end contracted to an axial perforation and slotted from said perforation longitudinally to the other end.

JOSEPH R. RAWLEY.
